UNITED STATES PATENT OFFICE

WILLIAM D. FERRIS, OF STERLING, ILLINOIS, ASSIGNOR TO FRANTZ MANUFACTURING CO., OF STERLING, ILLINOIS, A CORPORATION OF ILLINOIS

LATCH

Application filed April 11, 1928. Serial No. 269,262.

This invention relates to door latches, and more particularly to those for cabinets or cupboards, and especially those in which a pivoted latch is operated by a rotary knob.

One object of the invention is to provide a novel construction and arrangement whereby the two sections of the casing of the latch device, the one section in which the knob is swiveled and the other section on which the latch is pivoted, are rigidly fastened together, whereby the entire device is unitary in character.

Another object of the invention is to provide a novel construction whereby the pivoted latch is operated by the rotary knob through the medium of a reciprocating element that is not rigid with the latch, nor with the knob, and whereby a more satisfactory cam action is obtained, as well as other results, as will hereinafter more fully appear.

It is also an object to provide certain details and features of construction and combinations tending to increase the general efficiency and the desirability of a rotary-knob pivoted latch device of this particular character.

To these and other useful ends, the invention consists in the matters hereinafter set forth and claimed, and shown in the accompanying drawings, in which,—

Fig. 1 is a horizontal section through a portion of a cabinet door and the adjacent side wall of the cabinet, showing a rotary-knob pivoted-latch device embodying the principles of the invention, certain portions of the casing of said device being also shown in horizontal section.

Fig. 2 is a vertical, longitudinal section on line 2—2 in Fig. 1.

Fig. 3 is a vertical, transverse section on line 3—3 in Fig. 1.

Fig. 4 is a perspective of a portion of the sheet-metal casing involved in the construction of the said device.

Fig. 5 is a perspective of the reciprocating slide which is actuated by the cam on the inner end of the knob, and which in turn actuates the pivoted latch.

As thus illustrated, the invention comprises a casing composed of a cup-shaped

outer member 1, which is applied to the outer side of the cabinet door 2, and which is removably secured in place on the door by the screws 3 inserted as shown in Fig. 2 of the drawings. The casing also comprises the inner sheet-metal member 4 formed with feet 5 having holes 6 through which the grommets or rivet-like elements 7 are inserted to fasten the two sections of the casing together. The casing section 4 has parallel portions 8 provided with openings 9 through which the pivot 10 is inserted for pivoting the latch 11 in place in the casing. A coiled spring 12 is interposed between the latch 11 and the wall 13 of the casing. The inner section 4 of the casing also has a projection 14 that serves as a guide for the reciprocating slide 15, which latter has a notch 16 to receive the projection 14, whereby the slide 15 is prevented from rotating and is caused to reciprocate back and forth in a straight line by the cam 17, which is rigid with the inner end of the stem 18 of the rotary knob 19, which is centered on the outer section 1 of the casing. The knob 19 may be of any suitable material, but, for this style of latch and for certain purposes, is preferably of glass, being secured in the sheet-metal cup 20, which has a boss 21 that is mounted to rotate in the opening 22 in the outer section 1 of the casing, forming a rotary, swivel bearing. The squared stem 18 is made rigid with the boss 21 in any suitable or desired manner, and the cam 17 has a square opening to fit on said stem 18, and the latter is riveted over at 22 to permanently fasten the cam rigidly upon the inner stem portion of the knob. The slide 15 has shoulders 23 for engagement with the straight, upper edges 24 of the cam, whereby the rotation of the knob 19 in either direction will swing the latch 11 out of engagement with the strike piece 25, which latter is suitably secured to the side wall 26 of the cabinet or other structure.

In this way, therefore, the cam 17 acts upon a reciprocating element, the slide 15, which is maintained in a vertical plane, and which is not rigid with the latch, but which has engagement therewith, having an opening 27 to receive the outer end portion 28 of the latch, whereby rotation of the knob causes endwise

movement of the slide 15 in its vertical plane, and causes the disengagement of the latch 11 from the strike piece 25 on the inside of the cabinet. Also, with this construction, a portion of the casing, the portion 14, acts as a guide for the said reciprocating slide, and prevents rotation of the said slide when the said cam is rotated by the knob.

With this construction, as exemplified by the drawings, the entire pivoted-latch and rotary-knob device is a structural unit that can be applied to the door as a unit, and that can be removed without separating any of the parts thereof, and particularly without separating or detaching one section of the casing from the other. All that is necessary, in installing the latch, is to form the opening 29 in the door, for the inner section 4 of the casing, insert the screws 3 and secure the strike piece 25 in place.

It will be understood that the latch can be of any suitable or desired size. For some purposes, as on cabinets and cupboards the latch device can be much smaller than the one shown in the drawings.

Without disclaiming anything, and without prejudice to any novelty disclosed, what I claim as my invention is:

1. In a door latch mechanism, the combination of a mounting unit comprising an outer part and an inner part, the outer part being cup-like on its inner side, the inner part engaging within the outer part, having retaining means for holding the inner part in engagement with the interior of the outer part, a rotary knob swiveled only in the outer part and having its inner end provided with a swivel head disposed in the cavity of the outer portion and having a cam-like engaging portion, a latch member pivoted on said inner part and provided with means comprising a reciprocating slide for engaging said portion, said slide being movable back and forth in the plane thereof and having engagement with the latch member, a spring carried by the inner part and engaging said latch member, and a strike piece for engaging said latch member.

2. In a door latch mechanism, the combination of a mounting unit comprising an outer part and an inner part, the outer part being cup-like on its inner side, the inner part engaging within the outer part, having retaining means for holding the inner part in engagement with the interior of the outer part, a rotary knob swiveled only in the outer part and having its inner end provided with a swivel head disposed in the cavity of the outer portion and having a cam-like engaging portion, a latch member pivoted on said inner part and provided with means comprising a reciprocating slide for engaging said portion, said slide being movable back and forth in the plane thereof and having engagement with

the latch member, a spring carried by the inner part and engaging said latch member, and a strike piece for engaging said latch member, said inner part having means forming a guide, and said slide having means for engaging said guide, whereby to insure straight back and forth movement of said slide.

3. In a door latch mechanism, the combination of a mounting unit comprising an outer part and an inner part, the outer part being cup-like on its inner side, the inner part engaging within the outer part, having retaining means for holding the inner part permanently in engagement with the interior of the outer part, said inner part being of sheet metal bent to provide feet that engage the outer part, and also bent to provide flat parallel walls, a rotary knob swiveled only in the outer part and having its inner end provided with a swivel head disposed in the cavity of the outer portion and having a cam-like engaging portion, a latch member pivoted on and between said flat walls of said inner part and provided with means for engaging said portion, a spring carried by the inner part and engaging said latch member, and a strike piece for engaging said latch member.

4. In latch mechanism, the combination of an outer cup shaped casing section, an inner casing section, means to permanently secure the two sections together, so that the inner section is in permanent engagement with the outer wall of the outer section, precluding separation of the sections before the mechanism is fastened to the door, fastening means permitting removal of said mechanism with said sections inseparable and as a unit from the outer side of the door, a knob swiveled in said outer section, rotatable about an axis extending at right angles to both sections, a latch pivoted on said inner section, and a cam rigid with the inner end of the swiveled portion of said knob, said latch member having means for engaging said cam, the axis of the knob and the axis of the latch member being at right angles to each other.

5. In latch mechanism, the combination of a pivoted latch member, a rotary knob, the axes of the knob and latch member being at right angles to each other, a cam rigid with the knob, a reciprocating slide operated by said cam, means for guiding said slide, the latch member having operative engagement with the slide, whereby rotating of the knob operates the latch, and spring means for normally and yieldingly maintaining the latch in operative position.

6. In latch mechanism, the combination of an outer cup-shaped casing section, an inner sheet-metal casing section provided with projecting feet, means for securing said feet to the inner surface of the outer section, said inner section having flat parallel walls spaced

a distance apart, a latch member pivoted between said flat walls, a spring for normally and yieldingly holding said latch member in operative position, a knob swiveled in the outer section, and a cam rigid with the inner 5 end of said knob, said latch member having means for engaging said cam.

7. A structure as specified in claim 6, said inner section having a projection forming a guide, and said means for engaging said cam 10 comprising a reciprocating slide having means for engaging said guide and having also means for engaging said member.

8. A structure as specified in claim 6, said means for securing said feet to said outer section comprising hollow rivets, in combination with screws inserted through said rivets to secure the latch mechanism to a door, said feet being integral with said parallel walls and co-operating with said rivets and screws 20 to support said walls in rigid position in the door.

Specification signed this 2nd day of April, 1928.

WILLIAM D. FERRIS.
